UNITED STATES PATENT OFFICE.

HENRY ALBERT SCHMIDT, OF COMINS, MICHIGAN.

INTERNAL-COMBUSTION ENGINE.

Application filed October 14, 1926. Serial No. 141,503.

The object of my invention is to provide valving means for internal combustion engines to take the place of the various forms of poppet and sleeve valves now commonly used.

5 Another object of my invention is to provide a valving mechanism for internal combustion engines which will readily lend itself to any desired method of explosion timing.

10 Another object of my invention is to provide a valving mechanism for internal combustion engines which is of simple and cheap construction and which will operate more efficiently than the valving methods now used.

15 Another object of my invention is to provide a valving mechanism for internal combustion engines which will simplify the construction of cylinders and which will require the use of very few mechanical parts as compared with the valving mechanisms now commonly used.

20 Another object of my invention is to provide valving mechanism of the sliding type, wherein the various intake and exhaust port openings are operated in unison.

25 With these and other objects in view, my invention consists in the arrangement, combination and construction of the various parts of my improved device, as described in the specification, claimed in my claims and 30 shown in the accompanying drawings, in which:

Fig. 1 is a longitudinal cross section, taken on line 1—1 of Fig. 3, of an internal combustion engine having my invention embodied 35 therein.

Fig. 2 is a plan view of the head and manifolds of an internal combustion engine embodying my invention, the valve ports being shown in dotted lines.

40 Fig. 3 is a view taken on line 3—3 of Fig. 1.

Fig. 4 is a view taken on line 4—4 of Fig. 1.

I have shown an internal combustion engine 10 having a crankcase 11 with a crankshaft 12 positioned therein, and a cylinder block 13 having the cylinders 14, 15, 16 and 17 therein. The cylinder block 13 is provided with water spaces 18. Within the cylinders 14, 15, 16 and 17 are pistons 19, 20, 21 and 22 which are respectively secured to the crankshaft 12 by connecting rods 23, 24, 25 and 26, and by the bearings 27, 28, 29 and 30. Positioned upon the heads of cylinders 14, 15, 16 and 17 is a casting 31 having ports 32, 33, 34 and 35 therein which are positioned directly 50 over the upper ends of cylinders 14, 15, 16 and 17 respectively. The casting 31 is also

formed with water spaces 36 which are connected with water spaces 18 by the ports 37.

Positioned upon casting 31 is a plate 40 having apertures 41, 42, 43 and 44 therein, as 60 designated in Fig. 4, which apertures are so spaced as to align, when desired, with ports 32, 33, 34 and 35 respectively. A second casting 50 having apertures 51, 52, 53 and 54 therein is positioned upon plate 40 with its 65 apertures 51, 52, 53 and 54 adapted to coordinate or align with ports 32, 33, 34 and 35 respectively. Casting 50 is also formed with water spaces 55 therein which are suitably connected with water spaces 18 and 36. 70

Positioned upon casting 50 is a plate 60 which has apertures 61, 62, 63 and 64 therein, as shown in Fig. 3, positioned to align, when desired, with apertures 51, 52, 53, and 54 in casting 50, and ports 32, 33, 34 and 35 respectively in casting 31. Positioned upon plate 60 is another casting 70 which has apertures 71, 72, 73, 74, 75, 76, 77 and 78, as shown in Fig. 2, which are positioned in pairs so that 71 and 72 may coordinate with aperture 51 80 and port 32, 73 and 74 with aperture 52 and port 33, 75 and 76 with aperture 53 and port 34, 77 and 78 with aperture 54 and port 35. Casting 70 is also provided with water spaces 79 which may be suitably connected, as will 85 be readily understood, with water spaces 55, 36 and 18.

The paired apertures 71—72, 73—74, 75—76, and 77—78 are provided with housings 80. Intake manifold 81 is connected through 90 the housings 80 with the apertures 71, 73, 75 and 77; and the exhaust manifold 82 is connected through housings 80 with apertures 72, 74, 76 and 78 as shown in Fig. 2.

Casting 50 is provided at each end with 95 apertured tongues 56 and 57 which carry crankshafts 91 and 92 in suitable bearings. Crankshaft 91 has secured to its lower end a horizontally extending crankarm 93, which in turn has secured to its end a spindle or shaft 100 94. Crankarm 95 is secured to the upper end of crankshaft 91 and extends horizontally at right angles therefrom, and at an angle of 90° from the direction of crankarm 93. Secured to the end of crankarm 95 is an upwardly extending spindle 96. Spindle 94 is movably secured in a suitable bearing in the end of plate 40, and spindle 96 is movably secured in a suitable bearing in the end of plate 60. 105

Secured to the upper end of crankshaft 92 is a horizontally extending crankarm 101,

and secured to the end of crankarm 101 is an upwardly extending spindle 102 which is movably secured in a bearing in the end of plate 60. Secured to the lower end of crankshaft 92 is a horizontally extending crank-arm 103 which extends at an angle of 90° from the direction of crankarm 101 and has secured to its end a downwardly extending spindle 104 which is movably secured in a bearing in the end of plate 40. The crankshaft 92 is driven by the camshaft 110 which has secured to its upper end a cam 111 which is also secured to the lower end of spindle 104. Camshaft 110 has secured to its lower end a bevelled gear 112 which is operatively engaged with bevelled gear 113 on crankshaft 12. The camshaft 110 is supported in suitable bearings in crankcase extension 115 and cylinder block extension 116.

20 Castings 31, 50 and 70 are constructed and positioned to permit plates 40 and 60 respectively to slide with a circular motion between them, as shown. The apertures 41, 42, 43 and 44 in plate 40 are disposed at an angle 25 to each other as are the apertures 61, 62, 63 and 64 in plate 60, apertures 51, 52, 53 and 54 in casting 50 and ports 32, 33, 34 and 35 in casting 31, which is determined by the firing order of the cylinders 14, 15, 16 and 17. 30 Apertures 71 and 72, 73 and 74, 75 and 76, and 77 and 78 in casting 70 are likewise arranged at the same angle to each other as the apertures in plates 40 and 60 and castings 31 and 50, for the same reason. Bevel gear 35 113 on crankshaft 12 is so related to bevel gear 112 on camshaft 110 that camshaft 110 will rotate once while crankshaft 12 rotates twice. For the purposes of illustration, the firing order of cylinders 14, 15, 16 and 17 in the four 40 cylinder four cycle engine shown in Fig. 1 has been designated as 14, 16, 17 and 15. The piston 19 in cylinder 14 is shown at the upper end of its compression stroke, the piston 21 in cylinder 16 is shown beginning its 45 compression stroke, the piston 22 in cylinder 17 is shown beginning its intake stroke and the piston 20 in cylinder 15 is shown beginning its compression stroke. The crankarms 95 and 101 extend in the same plane and direction from crankshafts 91 and 92, while the crankarms 93 and 103 extend in the same plane and direction from crankshafts 91 and 92 but at an angle of 90° to the direction of the crankarms 95 and 101 so that a clockwise 50 rotation of crankshafts 91 and 92 will cause the apertures 61, 62, 63 and 64 in plate 60 to move in a circle and will also cause the apertures 41, 42, 43 and 44 in plate 40 to move in a circle thus causing the apertures 61, 62, 55 63 and 64 in plate 60 to follow 90° behind the apertures 41, 42, 43 and 44 in plate 40 as the crankshafts 91 and 92 are rotated. The casting 70 is stationary and the apertures 71 and 72 therein are so positioned that the partition 60 120 between the apertures 71 and 72 is direct-

ly above the aperture 51 in casting 50 and the port 32 in casting 31. This is also true of the partition 121 between apertures 73 and 74, partition 122 between apertures 75 and 76, and partition 123 between apertures 77 and 78 with relation to apertures 52, port 33, aperture 53, port 34, and aperture 54, port 35 respectively.

The length and width of each of the apertures 71 and 72 and the partition 120 are respectively equal to each other, and the apertures 73-74, 75-76, 77-78, and the partitions 121, 122, 123, and the apertures 61, 62, 63, 64 of plate 60 are of the same dimensions. The center to center length of the crankarms 95 and 101 are each equal or slightly greater than the width of each of the apertures 71, etc. as above stated. It will be noted that the apertures 51, 52, 53 and 54 are somewhat funnel shaped as their upper ends are each of sufficient size and shape to cover the area of the apertures 71, 72 and partition 120, while their lower ends are smaller and each of a size and shape sufficient only to cover the area of ports 32, 33, 34 and 35. The ports 32, 33, 34 and 35 are each of a size not greater than each of the apertures 71, etc. in casting 70,—apertures 61, etc. in plate 60, and the lower ends of apertures 51, etc. in plate 50; and the apertures 41, 42, 43 and 44 in plate 40 are of the same size and shape as the ports 32, etc. The center to center length of each of the crankarms 93 and 103 is equal to or slightly greater than the width of either of the apertures 51, etc., 41, etc., or ports 32, etc. The plate 60 is so positioned that when crankarms 95 and 101 are in the position of 12 o'clock, the aperture 61 will be parallel with them and beneath partition 120, as shown in Fig. 3,—the crankarms 93 and 103 driving the plate 40 are positioned to move 90° in advance of crankarms 95 and 101 and are therefore at three o'clock, and the aperture 41 in plate 40 is to the right of port 32 and aperture 51, as shown in Fig. 4, and the other apertures in plates 60 and 40 are in the relative positions shown in Figs. 3 and 4. It will thus be seen that the rotation of plates 40 and 60 clockwise from the position above described will first cause apertures 71, 51 and port 32 to be closed to each other,—a further quarter rotation will produce an open passage through apertures 72, 61, 51, 41 and port 32,—a half rotation will close both apertures 71 and 72,—a three-quarter rotation will produce an open passage through apertures 71, 61, 51, 41 and port 32, and a complete rotation will again close apertures 71 and 72, and 51 and port 32. The same result is obtained with reference to the other cylinders 15, 16, 17 although at different intervals as a result of the different angles of the apertures which lead to the various cylinders, the degree of inclination of which depends upon the number of cylinders and their firing order. In Fig. 1 the firing order 130

of the four cylinders is 14—16—17—15, thus the apertures for cylinder 14, the first to fire, may be taken as the standard of comparison,—the apertures for cylinder 16, the second firer, are inclined 45° to the right of the apertures of cylinder 14,—the apertures of cylinder 17, the third firer, are inclined 45° to the right of the apertures of cylinder 16, the apertures of cylinder 15, the fourth firer, are inclined 45° to the right of the apertures of cylinder 17.

As an illustration, I designate apertures 71, 73, 75 and 77 as intake ports by connection with the intake manifold 81,—and apertures 72, 74, 76 and 78 as exhaust ports by connection with the exhaust manifold 82. Then assuming that piston 19 in cylinder 14 is at the top of its compression stroke, as illustrated in Fig. 1, it will be observed that the aperture 61 in plate 60 is directly beneath the partition 120, thus closing both of the apertures 71 and 72, and that aperture 41 in plate 40 is to the right of the lower end of aperture 51, and the port 32, thus sealing the cylinder 14 for the explosion which occurs at the top of the compression stroke. It will then be observed that piston 21 in cylinder 16, which is next in the firing order, is just starting its compression stroke; aperture 63 in plate 60 is moving across aperture 75 toward aperture 76, and is partly beneath partition 122, and aperture 43 is to the right of port 34 and the lower end of aperture 53, thus sealing the cylinder 16 for the compression stroke. It will then be noted that piston 22 in cylinder 17, which is third in firing order, is just beginning its downward intake stroke, and that aperture 64 is coordinating with intake aperture 77, and that aperture 44 in plate 40 is coordinating with port 35 and the lower end of aperture 54, thus providing a free passage through the intake manifold 81 and the intake aperture 77 into the cylinder 17. It will then be noted that piston 20 in cylinder 15, which is the fourth in firing order, is just beginning its upward exhaust stroke, and that aperture 62 in plate 60 is just moving from under partition 121 toward exhaust aperture 74, and that aperture 42 in plate 40 is beginning to coordinate with port 33 thus moving toward a free passage from cylinder 15 through exhaust aperture 74 into the exhaust manifold 82. A further quarter rotation of plates 60 and 40 will move the apertures therein to hold cylinder 16 sealed for firing, and to close cylinder 17 for compression, to open cylinder 15 for intake and to open cylinder 14 for exhaust. As the rotation continues, the relative action with reference to the different cylinders will take place in the order described. It will be understood that my device may be readily adapted to operate upon engines having any given number of cylinders, and that the only alterations required would be in the change

of the number of apertures in the different slides and castings, in the angle of the crank-arms operating the slides to each other, and in the angle of the apertures cooperating with the respective cylinders to each other. 70

It will be noted that the partitions 120, etc. between apertures 71, 72, etc. in casting 70 are wedge shaped in longitudinal cross section. This construction is provided for engines which are not provided with forced fuel feeding mechanism, such as the engines of pleasure and commercial cars now in common use, in order that there may be no overlap between the opening of the intake passages and the closing of the exhaust passages 80 as the apertures 61, etc. swing from exhaust apertures 72, etc. to intake apertures 71, etc. This construction is not necessary in racing engines and such other engines as are provided with a forced fuel feeding mechanism, 85 as the pressure under which the fuel is introduced into the intake apertures will effectually prevent any trailing exhaust gases from slowing up or interfering with the passage of fuel into the cylinders. 90

It will also be understood that several pairs of sliding plates may be used instead of the single pair shown in the drawings, by disposing each pair of plates used over the particular cylinder or cylinders they are designed 95 to control, and that the number of plate driving mechanisms may be accordingly increased and suitably positioned for operation.

It will also be understood that the apertures 71, etc. 61, etc. 51, etc. 41, etc. and ports 100 32, etc. may be of any desired shape or size so long as apertures 61, etc. correspond in size, shape and position with apertures 71, etc. and partitions 120, etc., and apertures 41, etc. correspond in size, shape and position 105 with the ports 32, etc. and the lower ends of apertures 51, etc. and the length of the crankarms operating the plates are equal to the width or diameter of the apertures in their respective plates. 110

It will be obvious that various changes may be made in the arrangement, combination and construction of the various parts of my improved device without departing from the spirit of my invention, and it is my intention to cover by my claims such changes as may be reasonably included within the scope thereof. 115

What I claim is:

1. A valving mechanism for an internal combustion engine having an apertured combustion chamber and a reciprocating member operable therein, comprising a header member for said combustion chamber having a passage there-through aligned with the aperture in said combustion chamber through which explosive and exhaust gases pass into and out of said combustion chamber, apertured plates slidable in said header member for opening and closing the passage there- 120
125
130

through into said combustion chamber whereby the passage of explosive gases into and the passage of exhaust gases from said combustion chamber is coordinated with the movement of the reciprocating member therein.

2. A valving mechanism for an internal combustion engine having a plurality of combustion chambers with a single aperture in each and reciprocating members operable in said chambers, comprising a header member for said combustion chambers having passages there-through each aligned with the aperture in each of said combustion chambers through which explosive and exhaust gases pass into and out of said combustion chambers, apertured plates slidable in said header member for opening and closing said passages, whereby the passage of explosive gases into and the passage of exhaust gases from said combustion chambers is coordinated with the movement of the reciprocating members therein.

3. A valving mechanism for an internal combustion engine having an apertured combustion chamber and a reciprocating member operable therein, comprising a header member for said combustion chamber having a passage there-through aligned with the aperture in said combustion chamber through which explosive and exhaust gases pass into and out of said combustion chamber, apertured plates rotarily slidable in said header member for opening and closing the passage there-through into said combustion chamber whereby the passage of explosive gases into and the passage of exhaust gases from said combustion chamber is coordinated with the movement of the reciprocating member therein.

4. A valving mechanism for an internal combustion engine having a plurality of apertured combustion chambers and reciprocating members operable in said chambers, comprising a header member for said combustion chambers having passages there-through aligned with the apertures in said combustion chambers through which explosive and exhaust gases pass into and out of said combustion chambers, apertured plates rotarily slidable in said header member for opening and closing the passages there-through into said combustion chambers, whereby the passage of explosive gases into and the passage of exhaust gases from said combustion chambers is coordinated with the movement of the reciprocating members herein.

5. A valving mechanism for an internal combustion engine having an apertured combustion chamber and a reciprocating member operable therein, comprising a header member for said combustion chamber having a passage therethrough aligned with the aperture in said combustion chamber through which explosive and exhaust gases pass into

and out of said combustion chamber, apertured plates slidable in said header member, driving means for said plates operatively connected with said reciprocating member whereby said plates are moved to open and close the passage from said combustion chamber through said header member in coordination with the movement of said reciprocating member.

6. A valving mechanism for an internal combustion engine having a plurality of combustion chambers and reciprocating members operable therein, comprising a header member for said combustion chambers having passages there-through each aligned with the sole aperture in each of said combustion chambers through which explosive and exhaust gases pass into and out of said combustion chambers, apertured plates slidable in said header member, driving means for said plates operatively connected with said reciprocating members whereby said plates are moved to open and close the passages from said combustion chambers through said header member in coordination with the movement of said reciprocating members.

7. A valving mechanism for an internal combustion engine having an apertured combustion chamber and a reciprocating member operable therein, comprising a header member for said combustion chamber having a passage there-through aligned with the aperture in said combustion chamber through which explosive and exhaust gases pass into and out of said combustion chamber, apertured plates rotarily slidable in said header member, driving means for said plates operatively connected with said reciprocating member whereby said plates are moved to open and close the passage from said combustion chamber through said header member in coordination with the movement of said reciprocating member.

8. A valving mechanism for an internal combustion engine having a plurality of combustion chambers and reciprocating members operable therein, comprising a header member for said combustion chambers having passages therethrough aligned with the apertures in said combustion chambers through which explosive and exhaust gases pass into and out of said combustion chambers, apertured plates rotarily slidable in said header member, driving means for said plates operatively connected with said reciprocating members whereby said plates are moved to open and close the passages from said combustion chambers through said header member in coordination with the movement of said reciprocating members.

9. An internal combustion engine having a combustion chamber and a reciprocating member operable therein, said chamber having a common intake and exhaust port, a valving mechanism comprising a header

member for said combustion chamber having a passage there-through having intake and exhaust openings at one end thereof and having a single opening at the opposite end thereof aligned with said combustion chamber port, a pair of apertured plates slidable in said header member in parallel planes and adapted upon movement to open and close said passage through said header member in 10 timed relation to the movement of said reciprocating member in said combustion chamber.

10. An internal combustion engine having a plurality of combustion chambers and reciprocating members operable therein, said chambers each having a common intake and exhaust port, a valving mechanism comprising a header member for said combustion chambers, having a number of passages equal 15 to the number of combustion chambers, each of said passages having intake and exhaust openings at one end and a single opening at the opposite end aligned with a combustion chamber port, a pair of apertured plates slid- 20 able in said header member in parallel planes, and adapted upon movement to open and close said passages through said header member in timed relation to the movement of said reciprocating members in said combustion 25 chambers.

11. In an internal combustion engine having a combustion chamber and a reciprocating member operable therein, said combustion chamber having a common intake and

exhaust passage leading therefrom provided 35 with an intake and an exhaust port at its outer end, an apertured member movable across said passage for opening and closing said combustion chamber in coordination with the cyclic action of the reciprocating 40 member therein, and a second apertured member movable across said passage in coordination with said first apertured member for controlling the passage of fuel and exhaust gases to and from said combustion 45 chamber in coordination with the cyclic action of the reciprocating member therein.

12. In an internal combustion engine having a plurality of combustion chambers and reciprocating members operable therein, said 50 combustion chambers each having a common intake and exhaust passage leading therefrom which are each provided with an intake and an exhaust port at its outer end, an apertured member or members movable across 55 said passages for opening and closing said combustion chambers in coordination with the cyclic action of the reciprocating members therein, and another apertured member or members movable across said passages in 60 coordination with said first apertured member or members for controlling the passage of fuel and exhaust gases to and from said combustion chambers in coordination with the cyclic action of the reciprocating members 65 therein.

HENRY ALBERT SCHMIDT.
